UNITED STATES PATENT OFFICE

2,516,948

WATER-COOLED SILENCER

Roland B. Bourne, West Hartford, Conn., assignor
to The Maxim Silencer Company, Hartford,
Conn., a corporation of Connecticut

Application March 12, 1947, Serial No. 734,113

2 Claims. (Cl. 181—43)

1

This invention relates to silencers for the exhaust of internal combustion engines, particularly to such silencers as have cooling water introduced into the exhaust gas stream in such a manner that water spray and the exhaust gases are carried through the silencer together. The purpose of the invention is to improve the silencing efficiency of this type of silencer, while using few parts and those of simple construction and light weight. The improved silencer is of particular value for such uses as the silencing of the engines of submarines during surfacing, the silencer being flooded when the submarine submerges. Tests have shown that the silencer constructed in accordance with the present invention will reduce the sound level of the exhaust 10 db below the best of the silencers previously available for the purpose, while at the same time having a size and weight much less than such prior silencers.

The improved silencer operates upon a novel mode of coaction between an acoustic filter and gas-entrained cooling water. In the preferred embodiment the main channel through which the exhaust gas and cooling water flows is coupled to one or more resonance chambers or sidebranches, and is fitted with means causing a substantial portion of the cooling water to be deflected into the sidebranches. The combination of the effect of resonance in the sidebranches and the cooling and sound attenuating action of the water spray greatly increases the silencing efficiency both at high and low frequencies.

The extreme simplicity of the silencer is at once apparent from the drawings, in which

Fig. 1 is a median section taken longitudinally through the silencer;

Fig. 2 is a section on line 2—2 of Fig. 1; and

Fig. 3 is a detail plan of the downstream end of the inlet section of the main channel.

The silencer comprises a horizontally disposed cylindrical shell 10 having an inlet header 11, an outlet header 12 and an intermediate header 13 dividing the interior of the shell into two chambers 14 and 15. Through the headers 11, 12, and 13 pass respectively an inlet conduit 16, an intermediate conduit 17, and an outlet conduit 18. Collectively these conduits form the main gas and sound conducting channel, and the portions of the chambers 14 and 15 not occupied by the conduits serve as resonance chambers or sidebranches acoustically and physically coupled to the main channel at the gaps 19 and 20 between the sections of conduit. Preferably these gaps are of a length between 70% and 100% of the diameter

of the conduit, and are centered at a point between one-quarter and one-third of the length of the chamber measured from its upstream end. The two chambers are preferably of unequal size to broaden the band of frequencies attenuated by resonance, and their dimensions are chosen to produce maximum attenuation of the major frequencies occurring in the exhaust system of the engine to which the silencer is to be fitted. To prevent shock excitation of the intermediate and exhaust conduits the former is pierced with anti-resonance holes 21 located at the half and quarter points of the conduit as fully discussed in United States Patent 2,265,342, and the outlet conduit 15 provided with a slot 22 preferably positioned on the bottom of the conduit to assist in drainage of the chamber 15.

The downstream open ends of the conduits 16 and 17 are each fitted with a device which will cause water passing with the gas through the conduit to be deflected out into the chambers 14 and 15. This water is preferably supplied to the gas during its passage through the inlet conduit 16 through a series of holes 23 passing through the wall of that conduit into an encircling housing 24 provided with a pipe 25 through which water may be supplied from any desired source. Water enters the conduit simultaneously throughout its circumference and is carried away by the current of exhaust gas in the form of a spray. The deflecting device is preferably in the form of a scoop 26 in the form of half a cone with a 90° apex angle. The deflectors extend about half way across the open end of their associated conduits, and neither their size nor angle is particularly critical. They serve to deflect most of the entrained water into the sidebranches, although some water passes directly into the next conduit section and some more passes out through a hole 27 formed near the apex of the cone which is useful to permit rapid draining of the conduits when the submarine surfaces.

The chambers 14 and 15 are vented to atmosphere through openings 28 so that, upon submerging, these chambers completely fill with water, leaving no entrapped air which might disturb the trim of the vessel. A small opening 29 in the upper portion of the intermediate header 13 also assists in venting. The interior of the silencer is preferably coated with some protective material such as enamel, and by forming the shell 10 in two parts joined by a gasketed flange 30 the internal parts are made readily accessible for enamelling and at the same time provision is

made for holding the intermediate header 13 in place.

What I claim is:

1. A silencer having a substantially cylindrical casing, at least one transverse partition dividing the casing into a plurality of chambers, a substantially cylindrical conduit forming a gas and sound conducting channel passing in a substantially straight line through the several chambers, said channel having a gap opening into each chamber intermediate the length thereof, a water inlet delivering water into the channel at a point prior to the gap in one of the chambers, and a deflector located within each gap subsequent to the point of water introduction comprising a half cone whose axis is substantially coincident with that of the channel and whose half base is coincident with half of the channel at the upstream end of the gap to throw into each chamber the water entrained by the gas entering said gap. 15

2. A silencer having a substantially cylindrical casing, at least one transverse partition dividing the casing into a plurality of chambers, a substantially cylindrical conduit forming a gas and sound conducting channel positioned substantially tangent to the interior of said casing at one side thereof and passing in a substantially straight line through the several chambers, said channel having a gap opening into each chamber intermediate the length thereof, a water inlet 30

delivering water into the channel at a point prior to the gap in one of said chambers, and a deflector located within each gap subsequent to the point of water introduction comprising a half cone whose axis is substantially coincident with that of the channel and whose half base is coincident with half of the channel at the upstream end of the gap to throw into each chamber the water entrained by the gas entering said gap in a direction away from the line of tangency of the conduit and casing.
